WOOD PLANE

Howard H. Benn, Detroit, Mich.

Application February 12, 1943, Serial No. 475,599

2 Claims. (Cl. 145—15)

The present invention relates to improvements in wood planes and the like.

One of the objects of the present invention is to provide an improved wood plane.

Another object is to provide a wood plane having provisions for facilitating the removal of accumulated shavings.

Other objects and advantages residing in the combination, arrangement and construction of parts will more fully appear from a consideration of the following specification and the annexed claims.

In the drawing,

Fig. 1 is a plan view of the improved plane, Fig. 2 is a side elevational view of Fig. 1, partly shown in vertical cross section, and

Fig. 3 is a side elevational view of the pivotal blade unit removed from the main body.

Referring to the drawing, the principles of the present invention are disclosed in connection with a main plane body 10 having a rear portion 12, a front portion 14, and vertical side portions 16 and 18. Generally speaking, the improvements of the present invention in plane construction are subject to being embodied in planes of many shapes, sizes and types of constructions, and for this reason it is not my desire to limit myself to any specific type of plane or method of fabrication.

The structure for facilitating the removal of accumulated shavings comprises a hinged unit generally designated by reference character 20, having a main portion 24 which functions as a continuation of the bottom portion 22 of the main body 10. The bottom portion 24 is illustrated as having a thickened portion 26, having a hole 30 to receive the shaft 32, suitably supported at opposite ends in the sides 16 and 18. As more clearly shown in Fig. 1, the bottom portion 24 is supported in an opening 28 between the sides 16 and 18, and functions as the lower portion of a conventional plane which is usually an integral part of the plane body in lieu of being hinged as herein disclosed.

Threaded in the post 34 in the pivoted bottom portion 24 is a blade adjustment screw 36 having a knurled head 38. The opposite end of the screw 36 carries a T-shaped member 40 which rotates in a similarly shaped slot 42 in the cutting blade 44. It will be observed that the longitudinal axis of the adjustment screw 36 and cutting blade 44 may be in offset parallel planes or in angularly disposed planes without affecting the operative relative between the T-shaped member 40 and the slot 42.

The blade 44 is supported for sliding adjustment on the inclined portion 46, being held by a chip breaking plate 48 through tightening the knob portion 52, having a threaded shaft 54 operating in the threaded hole 56 in the boss 57 of the pivoted bottom portion 24. The slot 58 in the blade 44 permits adjustment of the blade with the members just described holding the blade firmly against the surface 46. In using the plane, one hand of the operator grips the knob handle 59 and the other the rear handle 60 which is supported in the hinged bottom portion 24.

The rear end 62 of the bottom portion 24 is beveled at 64 to rest on a similarly beveled portion 68 of the rear bottom portion 70 of the main bottom portion 10. With the beveled portions 64 and 68 engaging, the bottom portion 24 is in the plane of the front bottom portion 72 and the rear bottom portion 70 of the main body 10.

In dotted outline in Fig. 2 is illustrated the manner in which the pivoted bottom portion 24 of the plane is manipulated to facilitate the clearing of the shavings. For the reason that the operating pressure upon the pivoted bottom portion 24 is always in a direction urging the beveled portions 64 and 68 into firm engagement, my improved plane can be used without any latching mechanism for the pivoted bottom portion 24.

However, to assure the proper positioning of the bottom portion 24 with the plane in use, any suitable releasable latch may be used between the bottom portion 24 and the main body 10 of the plane. In the illustrated form, the handle 60 has a bore 73 to receive the push rod 74. The cam 76 at the lower end of the rod 74 acts upon a pin 78 carried by the latch pin 80. A spring 82 urges the latch pin 80 into engagement with a catch 82 and at the same time functions to hold the rod 74 in an elevated position. The lock pin 84 operating in the slot 86 holds the rod 74 and pin 80 in assembled relation. To pivot the bottom portion 24, the operator depresses the button 88 with his thumb at the top of the rod 74 to withdraw the pin 80 from the catch 82. Upon closing movement the inclined surface 90 will cam the pin 80 into engagement with the catch 82.

In Fig. 3 the pivotal blade unit and the attached handle is shown removed from the main body 10 by loosening the shaft 32, which is preferably in the form of a screw threaded into the side 18 and having a screw driver slotted head countersunk in the side 16. This unit when removed from the main body 10 is capable of being used as an additional tool for planing in

close quarters and for removing material directly adjacent the shoulder. In this connection the knob 52 serves the same function as the knob 59 in the assembly shown in Fig. 2. It will also be readily appreciated that the unit shown in Fig. 3 may be used in plane bodies corresponding to the main body 10 but of different lengths.

Having thus described my invention, what I desire to secure by Letters Patent and claim is:

1. A wood plane comprising a main body portion having a work engaging bottom portion with an opening defined therein, a second bottom portion located in said opening and pivotally supported intermediate its ends from said main body portion, a cutting blade supported on the forward end of said second bottom portion, said bottom portions being spaced at the forward end of said second bottom portion to define an opening through which the cutting blade of the plane projects to engage the work, abutment means supporting said bottom portions in the same plane by limiting pivotal movement of said second bottom portion in one direction, the forward end of said second bottom portion being swingable downwardly through said opening into a position

to clear shaving accumulations from said opening.

2. A wood plane comprising a main body portion having a flat work engaging bottom portion, an opening in said bottom portion defined by forward and spaced side portions thereof, a cutting blade supporting structure having a bottom portion, means for pivotally supporting said structure from said main body portion to pivot about a transverse axis intermediate the ends of said structure, the bottom portion of said structure being disposed in said opening and normally in the plane of said first bottom portion, a cutting blade carried by the forward end of said structure and projecting through a forward portion of said opening, said structure being swingable in said opening to a position facilitating the clearing of shavings and the like from that portion of said opening through which the cutting blade projects and co-operating abutment shoulders on said structure and main body for limiting the swinging movement of said structure in one direction to dispose said bottom portions in the same plane.
